(57) **CLAIM**

The ornamental design for a protective cover for a pharmaceutical vial, as shown and described.

DESCRIPTION

FIG. 1 is a perspective view a protective cover for a pharmaceutical vial, showing our new design from the top, front and side; and

FIG. 2 is a perspective view thereof as seen from the bottom, rear and side opposite of the side shown in FIG. 1; and,

FIG. 3 is a side elevation of the protective cover installed on a pharmaceutical vial represented in dashed line.

The dashed line showing of the vial in FIG. 3 is for illustrative purposes only and does not form part of the claimed design.
